MOTORCYCLE WINDSHIELD

Walter R. Hiatt, Long Beach, and Paul R. Jones,
Norwalk, Calif., assignors to Bates Industries, Inc.,
Long Beach, Calif., a corporation of California

Filed May 18, 1966, Ser. No. 2,340

Term of patent 14 years

Int. Cl. D12—11, 14

U.S. Cl. D90—1

FIG.1

FIG.2

FIG.3

FIG.4

FIG.8

FIG.5

FIG.7

FIG. 1 is a perspective view of a motorcycle windshield showing our new design;

FIG. 2 is a side elevational view thereof, the right side elevational view being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a fragmentary perspective view of a modified form of our design, which is identical to the design shown in FIG. 1 except for the configuration of the left and right side edges;

FIG. 8 is a fragmentary perspective view of a further modified form of our design, and it is identical to the design of FIG. 1 except for the configuration of the lower edge thereof.

The characteristic feature of our design resides in the compound curvatures of a motorcycle windshield that has a generally compound convex front face wherein the lower approximate one third portion is directed inwardly from the front face of the upper approximate two thirds portion and has a greater degree of vertical curvature than the upper two thirds and is made up of one curva-

ture from side to side and another curvature throughout the vertical height of the one third portion while the upper two thirds portion is made up of one curvature from side to side and another curvature throughout its vertical height.

We claim:

The ornamental design for a motorcycle windshield, substantially as shown and described.
